UNITED STATES PATENT OFFICE.

CORNELIUS A. DUGAN, OF MOUNT VERNON, NEW YORK.

SEAL FOR RECEPTACLES.

1,232,248.

Specification of Letters Patent.

Patented July 3, 1917.

Application filed December 29, 1916. Serial No. 139,625.

To all whom it may concern:

Be it known that I, CORNELIUS A. DUGAN, a citizen of the United States, residing at Mount Vernon, in the county of Westchester and State of New York, have invented new and useful Improvements in Seals for Receptacles, of which the following is a specification.

My present invention relates to improvements in seals of the class adapted to prevent malicious or unauthorized opening or tampering with the contents of receptacles. The object of the present invention is primarily to provide a seal of this class which is capable of effectually preventing unauthorized opening, either partially or wholly, of barrels when used as receptacles or shipping cases for goods or articles which it is desired to seal or prevent from theft or malicious tampering. The present invention provides a seal for barrels which will prevent removal or displacement of the barrel head either in whole or in part, the device being so constructed and arranged that it may be applied and removed easily and quickly by the proper authorities.

To these and other ends, the invention consists in certain improvements, and combinations and arrangements of parts, all as will be hereinafter more fully described, the novel features being pointed out particularly in the claims at the end of the specification.

In the accompanying drawings:—

Figure 1 is a perspective view of an ordinary barrel equipped with seals embodying the present invention.

Fig. 2 is an end view of the barrel showing the seal applied to one of the heads thereof.

Fig. 3 is an end view of a barrel showing another embodiment of the seal applied thereto.

Fig. 4 is a view similar to Fig. 3, showing substantially the seal illustrated in that figure but arranged somewhat differently to provide for a barrel head made in several pieces.

Fig. 5 is an end view of a barrel showing another embodiment of the seal applied to the head thereof.

Fig. 6 is a side elevation of one end of the barrel showing the manner in which the seal is preferably applied to the end hoop of the barrel.

Figs. 7 and 8 are detail perspective views

of the spider which forms part of the seal as shown in Figs. 3 and 4.

Similar parts are designated by the same reference characters in the several views. 60

The present invention is shown applied to barrels of ordinary construction, and certain embodiments of seals are shown in the accompanying drawings and will be herein-after described in detail. It is to be understood, however, that the invention is not restricted to the precise constructions and arrangements shown, as equivalent constructions and arrangements are contemplated and will be included within the scope of 70 the claims.

The barrel shown, and which is of the ordinary construction, comprises a body 1 composed of the usual bent segmental staves, heads 2 set in grooves or recesses formed in 75 the staves adjacent to their ends, and a suitable number of hoops 3 which bind together the staves and also retain the heads within the circular grooves formed in the staves. In some cases, the heads of the barrel may 80 be in one piece, as shown in Figs. 1 and 2, while in other cases, the heads may be formed in three pieces, as shown in Fig. 3, or in four pieces, as shown in Fig. 4.

The seal, as shown in Figs. 1 and 2, is 85 applied to the barrel by drilling a suitable number of holes 4 diagonally or in a direction slanting downwardly and outwardly through the barrel head, the staves, and the end hoop of the barrel. In the present 90 instance, four of these holes are shown spaced equidistantly in a circumferential direction. Also, a suitable number of holes 5 are bored or drilled through the staves and the end hoop of the barrel adjacent to 95 the holes 4, the holes 5 extending from the inner sides of the staves at approximately the level of the outer side of the barrel head, and these holes 5 also preferably slope downwardly and outwardly. Four of these 100 holes 5 are shown in the present instance, and these holes are preferably displaced in directions circumferentially and axially of the barrel with respect to the holes 4. The seal, as shown in Figs. 1 and 2, comprises a 105 length of wire 6, the ends or extremities 7 and 8 of which are secured together by any suitable sealing device 9, and the wire extends continuously in the form of a polygon across the outer face of the barrel head, the 110 wire at the apices of the polygon being twisted, as at 10, and formed into loops 11

which extend through the holes 4 and 5 and lap the outer side of the hoop. Owing to the different levels of the holes 4 and 5, the part 12 of each loop which laps the outer side of the hoop will extend diagonally of the hoop, and this is an advantage in those cases where the hoops are, as usual, made of wood, as the diagonal position of the loop relatively to the hoop will cause this part of the loop to cross the grain of the wood of which the hoop is composed and will thereby prevent splitting and unauthorized removal of the hoop. The wire is preferably applied to the barrel by threading its ends through the circumferentially spaced holes 4 and 5 in the barrel, the ends of the wire being finally brought together and secured by the sealing device.

In some cases, it may be preferable to employ a frame or spider to assist the wire in preventing unauthorized removal or displacement of the barrel head, particularly where the barrel head is composed of several pieces or is split. Such arrangements are shown in Figs. 3 and 4. In these instances, a frame or spider is shown which is composed of a pair of cross-arms 13 and 14, these cross-arms being connected at their center or point of intersection by a pivot or eyelet 15, and they are provided at points adjacent to their extremities with openings 16, which openings are adapted to overlie the inner ends of the openings 4 in the barrel head, and those portions of the wire which extend through the openings 4 also extend through these openings 16 in the frame or spider. By connecting the bars or members 13 and 14 of the frame or spider pivotally, these bars or members may be set in different angular relations. For example, in Fig. 3, the bars or members of the frame or spider are in right angular relation to conform to an arrangement wherein the wire-receiving holes in the barrel and its head are equidistantly spaced circumferentially of the barrel. This arrangement is satisfactory where the barrel head is composed of one, two or three pieces. In other cases such, for example, as where the barrel head is composed of four pieces, as indicated in Fig. 4, the bars of the frame or spider may be set at a different angle so that one of the bars will cross the barrel head sections at substantially a right angle while the other bar of the spider will lap the central joint between the barrel head sections diagonally. In this latter instance, the holes 4 and 5 in the staves, hoop and head of the barrel may be located to conform to the angular arrangement of the bars of the spider.

In some instances such, for example, as where the barrel head is composed of more than four pieces, or where the head is lacking, a disk 17 of relatively thin but tough

material, such as heavy cardboard or other fibrous material, may be provided in cases where the disk is used in connection with the barrel head, or where the head is lacking, the disk may be composed of wood or metal. This disk conforms preferably to the opening in the end of the barrel and is provided at circumferentially spaced points with openings 18 through which portions of the sealing wire extend so that those portions of the loops which extend through the holes 4 in the staves and hoop will lie at the inner side of the disk, and those portions of the loops which extend through the holes 5 in the staves and hoop will lie at the outer side of the disk. By this arrangement of the wire, the disk is sealed in place and it is held from displacement either inwardly or outwardly. The wire may be threaded through the holes in the staves and hoop and through the openings in the disk and brought together and secured by the sealing device, as in the preceding instances. Preferably, eyelets 19 are fitted to the disk 17 and surround the openings 18 therein.

Where a spider or frame is used in connection with the sealing wire, these spiders may be collapsed so as to occupy a relatively small space by swinging the bars composing the spider into parallelism, as shown in Fig. 8. Also, by employing an eyelet for the pivot 15 connecting these bars, a cord or wire may be passed through these eyelets and may thus serve to hold a large number of the spiders in readiness for use.

The present invention provides a seal for barrels and equivalent receptacles which occupies such a position relatively to the barrel head that it is protected from accidental breakage during handling of the barrel, the wire being contained in the depression at the end of the barrel and lying close to the head, and rolling of the barrel will not break the sealing device as the convexity of the barrel will so support it that the sealing devices at the smaller ends of the barrel will not come into contact with the floor or ground on which the barrel is rolled. The disposition of the sealing wire relatively to the head is such that unauthorized removal or displacement of its parts, irrespective of whether the head is in one piece or in sections, is practically prevented. By looping the sealing wire through the end hoop of the barrel, removal of this hoop is prevented and, in consequence, it would be impossible to remove the head from the groove in the staves which retain the head in place.

I claim as my invention:

1. A seal for use in connection with a receptacle and closure therefor, the receptacle having pairs of openings therein spaced at intervals around the closure, and the closure having an opening in alignment with one

opening of the respective pair in the receptacle, comprising a sealing wire extending across the face of the closure and having portions looped through the respective pairs 5 of openings, the ends of the loops where they join the remainder of the wire being twisted.

2. A seal for use in connection with a barrel having a head closing an end thereof and 10 a hoop for retaining the head in place, comprising a wire extending across the outer face of the head and through the head and hoop to retain the head and hoop in coöperative relation with the body of the barrel, 15 and a sealing device coöperative with the wire to prevent removal thereof.

3. A seal for use in connection with a barrel having a head closing an end thereof, and a hoop for retaining the head in place, 20 pairs of openings extending through the hoop at different points in the width thereof, comprising a sealing wire extending across the outer face of the head and looped through said pairs of openings in the hoop, 25 portions of the loops of the sealing wire also extending through the head.

4. A seal for use in connection with a barrel having a head to close one end thereof, and pairs of openings extending through 30 the body of the barrel, an opening in alinement with one opening of each pair extending through a portion of the head and the other opening of each pair being located in the body of the barrel at the outer side of 35 the head, comprising a sealing wire having portions looped through the respective pairs of openings and other portions extending across the outer face of the head.

5. A seal adapted for use in connection

with a receptacle and a closure, the receptacle having pairs of openings therethrough spaced around its periphery adjacent to the closure and the closure having openings extending therethrough, each opening in the closure being in alinement with one opening 40 of each pair in the receptacle, the seal comprising a spider adapted to lie against the outer side of the closure and having openings to register with those in the closure, and a sealing wire extending across the 45 outer side of the closure and spider and having portions looped through the pairs of openings in the receptacle and the openings in the closure and spider.

6. A seal for fastening a closure to a receptacle, the receptacle having pairs of openings extending therethrough at intervals around its circumference adjacent to the closure and the closure having openings each in alinement with one of the openings 50 of each pair in the receptacle, the seal comprising a spider composed of pivotally connected members adapted to extend across the outer face of the closure, the members having at their ends openings to register 55 with those in the closure, and a sealing wire extending across the outer side of the closure and spider and having portions thereof looped through the openings in the spider and closure and through the pairs of openings in the receptacle.

In testimony whereof I have hereunto set my hand in presence of two subscribing witnesses.

CORNELIUS A. DUGAN.
